COMBINED INK BOTTLE HOLDER AND PEN RACK

Sheldon Alan Wallerstein, Silver Spring, Md., and Edward Bernard Stewart, Washington, D.C., assignors of one-third to Donald Allen Kaul, Washington, D.C.

Filed Feb. 17, 1964, Ser. No. 78,646

Term of patent 14 years

(Cl. D74—5)

FIG. 1

We claim:

The ornamental design for a combined ink bottle holder and pen rack, substantially as shown and described.
